UNITED STATES PATENT OFFICE.

JOHN J. M. WEIGAND, OF BELLEVUE, KENTUCKY, ASSIGNOR OF ONE-HALF TO MATTHEW J. MALONEY, OF BELLEVUE, KENTUCKY.

CARTON FOR MUSIC RECORD REELS.

Application filed October 7, 1921. Serial No. 506,071.

To all whom it may concern:

Be it known that I, JOHN J. M. WEIGAND, a citizen of the United States, and residing at Bellevue, in the county of Campbell and

5 State of Kentucky, have invented a new and useful Improvement in Cartons for Music Record Reels, of which the following specification is a full disclosure.

My invention relates to a carton or container for individually packing a record roll 10 for use on mechanical instruments.

An object of the invention is to provide a carton or container for a record roll, in which the roll can be permanently housed 15 and journaled, allowing the roll and its container to be applied in a mechanical musical instrument, without removing the roll from the carton or container, for use in either unreeling or reeling the record web.

20 Other features and objects of the invention will be more fully set forth in the description of the accompanying drawings, forming a part of this specification, and in the drawings like characters of reference 25 denote corresponding parts throughout the several views, of which:

Fig. 1 is a side elevation of my improved music record roll carton or container.

Fig. 2 is a section on line 2, 2, Fig. 1.

30 Fig. 3 is a view similar to Fig. 1, with parts broken away to show the music record roll journaled within the container, with the end of the roll provided with a clip engaged through a slot in the container.

35 Fig. 4 is a partial section on line 4, 4, Fig. 3.

Fig. 5 is a detail view showing the music record roll container mounted within a musical instrument.

40 Fig. 6 is a section on line 6, 6, Fig. 5.

Fig. 7 is a central section through a modified form of container.

Music record rolls, composed of a record strip of paper wound upon a reel or spool, 45 are commercially packed in individual containers or cartons which are suitably labeled and indexed for identification of the musical composition, which the record strip mechanically reproduces when operatively connected within a mechanical musical instrument.

The record roll under the prevailing practice must always be removed from its identifying container for use, and is, therefore, frequently placed in the wrong container, and the repeated handling in removing and 55 inserting the record roll for and after each instance of use is injurious to the record strip, as it is easily torn.

I, therefore, provide a carton or container from which the record roll is not removed 60 for use. The reel or spool upon which the record strip or web is wound, is journaled within and accessible from the exterior of the opposite ends of the container, so that the spool housed within the container can 65 be applied or inserted between the roll supporting spindles of the mechanical musical instrument in the usual manner, and as convenient as if the roll were removed from the container. There is no change in the 70 operation of the musical instrument or roll either in unwinding the record sheet from the reel while playing or in rewinding it.

Referring to the drawings, 1 indicates the rectangular container, preferably made of 75 cardboard material, with one of the walls 2 serving as a hinged cover for accessibility and having a tucking flap 3, as shown in Fig. 2. The wall 2 is adapted to be swung outwardly for opening the container for inserting or removing the record roll, consisting of a reel or spool 4 upon which the music record strip or web 5 is wound. The spool is of the commercial type of construction, having hubs 6 projecting or extending 85 respectively from the opposite ends or heads of the spool. The hubs engage and journal each in a respective orifice 7 centrally through the end walls 8 of the container, the spool therefore being freely journaled 90 within the container for unwinding or rewinding the music record strip from or upon the reel. The end faces of the hubs of the spool are socketed and key-slotted for rotatively connecting the spool between the 95 spindles 9, 9, of the mechanically operated musical instrument.

The front wall 10 of the container is slotted, as at 11, longitudinally approximately 100 its entire length or dimension, which slot is

designed to freely admit the entire width of the record strip, said strip passing freely therethrough during unreeling or reeling. The wall 10, on its interior face, is provided with a reenforcing strip 12 marginally binding the opening 11. This reenforcing strip at its intermediate and central portion is provided with opposingly extended lips 13, which reduce the area of opening or slot 11, 10 and overlie the slot edges of the wall 10, thereby forming in conjunction with the circular notches 11^a, middlemost of the slot 11, a recess 14 of circular outline, in the medial portion of the wall as a pocket to receive the ring 15 tabbed centrally upon the end of the record strip. The extension 13 of the reenforcing strip reduces the area of the slot 11 at the central portion of the carton sufficiently to prevent the ring 15 20 from being drawn through the slot, into the interior of the container, leaving the ring disposed within the grasp of the operator, the recess in the wall socketing the ring below the outside surface of the front wall 10, 25 so as not to form an obstruction.

As shown in Figs. 5 and 6, the record strip in use, as unwound from the spool, passes through the slot or opening 11 of the container, thence over the tracker-bar 17 and 30 upon the reel 16 of the musical instrument, which is of general construction. The ring at the end of the record strip is anchored upon a hook recessed within the periphery of the reel 16.

35 The lips 13, which may be referred to as a part of the wall 10, are depressed from the face side of the wall and integral therewith instead of being an extension of the liner or reenforcing strip. They, aside from reducing the opening area of the wall, serve to brake the traveling web both for unwinding and rewinding, and are especially serviceable for rewinding to tautly coil the web upon the reel. For rewinding, the operator 40 can grasp the carton with the thumb bearing upon the upper lip and by pressing the same inward can regulate the reeling tension. The lips also serve to tracker the web to avoid undue sidewise motion of the web. The ring 45 15 is provided with a central cross-bar 20, as an anchoring bar, about which the end of the record web is tapered for securing the ring to the web, usually a fabric tape is employed and adhesively secured to the end 50 of the web. The web is therefore secured to the ring diametrically, whereby the ring is in a position angular to the plane of the web and crosswise of the carton slot, thereby engaging both of the opposing lips and in 55 plane therewith to block any possibility of the ring being drawn through the carton slot, and the ring is always presented below the face surface of the carton.

As shown in Fig. 7, the opening in the

container through which the record strip 65 passes is located at one corner or edge of the container instead of centrally through one wall and the opening edges reenforced by a binder 18, the location of the opening being optional to meet service desire. 70

The container is of an internal dimension which will compactly house and sustain the record roll, but sufficiently loose for free rotation of the roll.

Having described my invention, I claim: 75

1. A container for music-rolls providing an enclosing box, having a lid and providing a lengthwise slot, end bearings in said box for the rotative support of a spool upon which a music sheet is wound, said slot providing passage for said music sheet, and the ends of said spool of a structure adapted to engage with the roll-journals of a player piano, for rotation of said spool independently of said box. 80

2. In a device of the class described, a container having its opposite ends apertured for supporting and journaling a reel within the container, a longitudinal slot in one of its side walls, through which a record web 90 moving upon the reel is drawn, and a reel having hubs projecting from its opposite ends and engaging into the apertures in the ends of said container and accessible from the exterior of the container for connection 95 with the reel journals of a mechanical musical instrument.

3. A device for permanently housing a music record reel comprising a container having its opposite ends apertured for supporting and journaling a record reel within the container, and provided with an opening longitudinal with the axis of the reel through which a record strip for the reel passes, said opening being constricted at the 100 medial portion thereof.

4. A device of the character described, a container having its opposite ends centrally apertured for supporting and journaling therein a reel having a record web wound 110 thereon, said container having a longitudinal slot parallel with the axis of the reel supported and journalized therein through which the record web is drawn, a lip extending to constrict the central portion of said slot and recess inwardly from the surface of said container for receiving a ring secured to the end of the record web, for preventing the web from being drawn inaccessible into said container. 115

5. In a device of the class described, a container having its ends apertured for supporting and journaling a record reel therein and provided with a slot through which a record web is drawn for unwinding and rewinding upon said reel, a reel having hubs projecting from its opposite ends engaging into the apertured ends of said container, 120

said hubs being accessible from the exterior of the container, and a record web for said reel, and a ring having a diametrical cross-bar fixed to the end of said web, providing 5 a stop for preventing the end of the web from being drawn inaccessibly through said slot.

In witness whereof, I hereunto subscribe my name, as attested by the subscribing witness. 10

JOHN J. M. WEIGAND.

Witness:

BERTHA SCHLAN.
